 Virginia

Application April 29, 1938, Serial No. 205,088

16 Claims. (Cl. 197—16)

The present invention relates to printing machines and more particularly to a printing machine which is designed and constructed in such manner as to have the capacity to print, upon a web of paper, words and lines comprising assembled letters of relatively large size, varying for instance from 18 point letters to 60 point letters. Primarily the machine is intended to comprise one of several units by means of which newspapers, magazines, books, periodicals, advertising folders and the like, may be printed without the necessity of casting or setting type.

As is well-known, the individual letters of a font of printer's type vary in width and in the completed printed line the letters are equidistantly spaced from each other. On the other hand the usual typewriter embodies type faces of uniform width so that the appearance of a completed typewritten line is substantially different from the appearance of a completed printed line. It has heretofore been proposed, however, that by the addition of a variable spacing mechanism to a typewriter, and providing the typewriter with type the faces of which differ in width as do the printer's type, the product of the typewriter may be caused to resemble very closely the product of a printing operation. It has, however, not been found heretofore to be possible to modify the usual typewriter by the addition of variable spacing mechanism to produce the effect of printed lines where very large type faces are to be employed.

The principal purpose of the present invention is to provide a printing machine, generally analogous to the variable spacing typewriter, by means of which printed lines and words the individual letters of which are of large size, may be rapidly and conveniently produced, the individual letters of the words being spaced apart as though actually printed with printer's type so that the completed product is indistinguishable from the product of the printing press. The novel machine includes a paper carriage in which the paper to be printed is guided for movement in a predetermined plane, a movable type carrying member which is so designed and so mounted that any desired letter may be brought into printing position with respect to the paper, and upon one side of the paper, and a printing head upon the opposite side of the paper which serves, when actuated, to press the paper against the previously inked letter and to be thereafter retracted to enable the paper to draw away from the type.

The actual printing operation is performed in

a novel manner, the printing head being of such character as to be movable in a plane parallel to the plane of the paper during printing operation, the actual paper engaging surface of the printing head rolling over one surface of the paper to insure perfect contact of the area of the surface to be printed with all areas of the ink carrying type and as a result of this more perfected printing of large characters than has heretofore been possible is realized.

The apparatus is motor driven and key controlled, the depression of a key effecting the connection of the printing mechanism to a constantly running motor whereby the printing mechanism is moved through one complete cycle of operations, the connection to the constantly running motor being automatically broken at the completion of such cycle of operations. The mechanism embodies many novel features of construction which will be hereinafter described in detail. A preferred embodiment of the invention is illustrated in the accompanying drawings but it will be appreciated by those skilled in the art that numerous variations in the details of the elements and subcombinations of elements may be effected in adapting the invention for special purposes and that that form thereof which is illustrated, and which is to be herein-after described, is set forth by way of example only.

In the drawings:

Figure 1 is a plan view of the machine, the housing having been removed;

Figure 2 is a side view of the machine partially in elevation and partially in section;

Figure 3 is a vertical longitudinal section taken on line 3—3 of Figure 1;

Figure 4 is a section on the line 4—4 of Figure 3;

Figure 5 is a plan view of a portion of the mechanism shown in Figure 3, showing the edges of the character selection track and cooperating members, the selection cog wheel and selection pawl arm mounted therebetween;

Figure 6 is an elevation taken on line 6—6 of Figure 3;

Figure 7 is a section on line 7—7 of Figure 2;

Figure 8 is a section taken on lines 8—8 of Figures 1 and 2;

Figure 9 is a section taken on line 9—9 of Figure 2;

Figure 10 is a view of part of the mechanism shown in Figure 9, on a somewhat larger scale, showing a portion of the spacing mechanism;

Figure 11 is a partial section on line 11-11 of Figure 10;

Figure 12 is an elevation of portions of the mechanism shown in Figure 10, as seen from the line 12-12 of that figure;

Figure 13 is a plan view on enlarged scale and partially broken away, of the printing head assembly;

Figure 14 is a section on line 14-14 of Figure 13;

Figure 15 is a section taken on line 15-15 of Figure 14;

Figure 16 is a section on line 16-16 of Figure 2;

Figures 17 and 18 are details of portions of the disc locking mechanism;

Figures 19, 20 and 21 are elevations showing the positions of the gears at, respectively, the beginning of a cycle, the beginning of the printing portion, or second third, of a cycle, and the beginning of the repositioning, or last third, of a cycle, portions A showing the character selection gears, portions B the gears which operate the printing head assembly, and portions C the repositioning mechanism operating gears;

Figure 22 is a sectional view through portions of the carriage and its slide controlling members;

Figure 23 is a horizontal section showing the carriage pinions and their key connection shift;

Figure 24 is an elevation of a portion of the type disc and the shield therefor;

Figure 25 shows in side elevation an operating key and the key locking mechanism;

Figure 26 is a detail of the spacing disc shifting cam;

Figure 27 is a detailed elevation of a portion of the character selector pin releasing mechanism;

Figure 28 is a series of detailed elevations of a portion of each of the supports of the keys shown as a column in Figure 1; and

Figure 29 is a bottom view of a key and its support.

The several portions of the machine of this invention are supported on a frame 30 the details of which are not important and need not be described. A motor 31 is connected through suitable gears such as are shown at 32 to a drive shaft 33 which is rotatably supported by the frame 30. A single revolution clutch 34, of a well-known type, connects the shaft 33 with the shaft 35 so that when the motor 31 is in continuous operation the clutch 34 may be operated to impart one revolution to the shaft 35. This will cause the machine as a whole to complete one cycle, that is, print one character of type and return to a normal position in readiness for another cycle of operation to print another character.

A suitably constructed typewriter keyboard 36 bearing any desired number of keys 37 is mounted at the front of the machine for easy manual operation. Each of the keys 37 is pivotally connected to a bell crank lever 38 which is pivotally mounted on the frame 30 and which is normally held in the position shown by a tension spring 38'. Each of the bell crank levers 38 is pivotally secured to one end of a rod 39', the other end of which is pivotally secured to one arm of an associated bell crank lever 39, levers 39 being pivotally attached to the frame 30 as at 40. The other arm of each lever 39 is pivotally connected to a vertical link 41 which, through another lever or bell crank 42, pivotally secured as at 43

to a stationary disc 44, causes one of a series of blocks 45 to move forwardly away from its normal position, blocks 45 being shown in normal positions in Figure 2. The several levers or bell cranks 42 are so shaped that the pins which connect them to the blocks 45 are all horizontally disposed. It will be seen from the drawings that each of the keys 37 is independently connected with one of the blocks 45 and through the above described lever system a definite block 45 is moved out, or to the left in Figure 2, as a definite key 37 is depressed.

The single revolution clutch 34 is held in the open position shown in Figure 2 by a sear 127, on a cam 128, contacting a bell crank trigger 129 which is pivoted to the frame 30 at 130. Each of the levers 39 carries a boss 131, any one of which when moved by the depression of any key 37 moves a crossbar 132 which, through a lever 133, pivoted to the frame 30, a link 134, a bell crank 135, pivoted to the frame 30, and a vertical link 136 moves the trigger 129 out of engagement with the sear 127. This permits a compression spring 137 to close the clutch 34 permitting the continuously running motor 31 to drive the main shaft 35. The shaft 35 is thereby turned through 360 degrees being thereby stopped by the action of the trigger 129 on the cam 128 to again throw the clutch 34 out of engagement. A compression spring 137', mounted between the crossbar 132 and any stationary part of the machine, urges this bar 132 and the lever system connected thereto back to the normal position when displaced therefrom.

In order that a depressed key (see Figure 25) may remain depressed long enough and yet not too long, another boss 39' on the lever 39 and another cross bar 391 are provided for holding the key which is depressed for a definite length of time. This is accomplished by mechanism, which will be described later, for raising the bar 391 to the position shown in solid lines in Figure 25 as soon as the boss 39' has crossed to the rear of said bar 391. The raising of the bar 391 also serves to prevent a second key from being depressed during the following interval.

The stationary disc 44 bears on the upper 180 degrees of its periphery a plurality of keyways 46 in which the blocks 45 are slidably mounted, there being one block for each of the keys 37 of the keyboard. These blocks 45 are so arranged that, when they are all in position, they form a continuous half-cylindrical surface which approximates a smooth surface.

On an axis passing through the center of curvature of the substantially continuous surface formed by the blocks 45 there is rotatably mounted a selection pawl arm 47 and a selection cog wheel 48. The selection pawl arm 47 is keyed as at 49 to a shaft 50, while the selection cog wheel 48 is rotatably mounted on the same shaft. The selection pawl arm 47 is rotated, when the shaft 35 is rotated, at the beginning of a cycle, for the first one-third of the cycle, by means of a gear train consisting of a 120 degree segment gear 51 engaging gear 52 which through a shaft 53 rotates a gear 54 which engages a pinion 55 which is secured to the shaft 50 upon which said arm 47 is mounted. This gear ratio is such that 120 degrees of revolution of the gear 51 turns the pawl arm 47 through 180 degrees. The portions "A" of Figures 19, 20 and 21 show, respectively, the positions of the above mentioned gears, at the beginning of a cycle, during the first one-third of a cycle and at the end of 120 degrees

of rotation of the main shaft 35 or of the gear 51. It will be noted from Figure 4 that the selector pawl arm 47 is symmetrical and carries identical members at each end, thus requiring a revolution of only 180 degrees per cycle of the machine as a whole, to place it in the proper position for the beginning of the next cycle.

When any one key is depressed, since one of the blocks 45 is moved, an opening such as is shown at 56, Figures 3 and 5, is left in the formerly smooth surface. A pawl 57 is mounted on each end of the pawl arm 47 so that one of the pawls 57 wipes the surface formed by the blocks 45 and will fall through any opening 56, if such an opening exists, when the pawl arm 47 is being rotated. This movement of the pawl 57 permits a dog 58, mounted opposite thereto, to engage the selection cog wheel 48. After this engagement the pawl arm 47, through dog 58 drives the cog wheel 48 through the remaining portion (see Figure 20) of the 180 degree angle which the pawl arm 47 rotates during the first one-third of each cycle. The cog wheel 48, which is rotatably mounted with respect to the shaft 50, has a gear 59 coaxially mounted and secured thereto by means of a bolt 60. A pinion 61 engages the gear 59 and through a shaft 62 borne by the frame 30 a type disc 63 is rotated. The selection cog 48 is geared to the type disc in a 2:1 ratio, so that when the selector arm 47 is turning through an angle ϕ the type disc is turning through the angle 2ϕ to bring the character of the key which was depressed into the printing position. One or more fonts of characters 63' may be mounted in concentric circles on the type disc face. One font forms one circle and any character thereof may be brought into a given position by the energy supplied through the pawl arm 47 as previously described, the possibility of a complete revolution of the type disc 63 depending only upon which of the blocks 45 is moved. It will be seen that by pressing one of the keys 37 a certain and dependent angle of revolution for the type disc 63 has been selected which brings the wanted character into a desired position—the printing position. This has been accomplished in 120 degrees of rotation of the main shaft 35.

Upon the completion of the previously described first one-third of a cycle the printing mechanism begins to operate, the printing operation being completed within the second one-third of the cycle. A second 120 degree segment bevel gear 64 secured to the shaft 35 supplies the energy for this portion of the cycle. Portions "B" of Figures 19, 20 and 21 show the relative positions of the segment gear 64, respectively, at the beginning of a cycle, at the beginning of the printing operation and at the completion thereof, with respect to a bevel gear 65 the location of which in the machine is best seen in Figure 2. The gear 65 is secured to the lower end of a vertical shaft 66 which is supported by the frame of the machine and carries on its upper portion a plurality of identical cams 67, 68 and 69. The gear ratio between the segment gear 64 and the bevel gear 65 is 3:1, thus causing the cams 67, 68 and 69 to make a complete revolution during the second one-third of a cycle. At the elevations of said three cams 67, 68 and 69, slide bars 70, 71 and 72 are mounted for both a forward and a rearward sliding motion and for rotation about a vertical axis 74 passing therethrough. A hollow guide member such as 73 is provided for each of the slide bars which pass therethrough,

these slide bars being longitudinally slidable with respect thereto. Each of the hollow guide members 73 is pivoted on the vertical axis 74 permitting the slide bars 70, 71 and 72 to be moved in their respective horizontal planes. A roller 75 is mounted on the rear end of each of the slide bars 70, 71 and 72, each of the rollers 75 contacting the respective cams 67, 68 and 69. The forward ends of the slide bars 70, 71 and 72 each have a printing head 76, 77 and 78 respectively, pivotally mounted thereon which may be faced with any desirable cushioning material 79. Small tension springs 80 connect the forward portions of each of the printing heads 76, 77 and 78 with the respective slide bars 70, 71 and 72 giving the printing heads an urge to return to the normal position when not being moved and at the same time providing a paracentric action so that any of the printing heads which are not in use during a given cycle may be held out of the way as shown by printing head 77 in Figure 13. The shaft 66 has a chain gear 81 secured thereto which by means of a chain 82, a chain gear 83, and a vertical shaft 84 borne by the frame 30 of the machine drives the cams 85 at a one-to-one ratio with the cam 67. The several cams 85 are proportioned to the width of the widest character of the font which is printed by the respective printing heads 76, 77 and 78. The cam 67 first furnishes forward motion to the printing head 76 and holds it forward for a time during which the cam 85, through a roller 86 supported by the guide members 73, imparts a lateral component to the printing heads 76, 77 and 78 and their supporting members, causing the printing head which is in use to roll across the face of a character on the disc 63. This lateral motion is opposed by a compression spring 87, secured to the machine frame, which serves to preserve contact between the roller 86 and the cam 85. Small tension springs, such as 88, connected between the slide bars 70, 71 and 72 and the guide members 73 preserve contact between the cams 67, 68 and 69 and the rollers 75.

It will thus be seen that during this second one-third of a cycle the printing head 76, or whichever one of the others is in use, will be forced against paper 89 with a forward motion derived from the cam 67 and then a rolling motion derived from the cam 85, pressing the paper 89 against the character on the printing disc 63 which was placed in the printing position in the first one-third of the cycle.

It is now necessary to space the copy by the width of the character just printed, possibly to index the copy for the next line of print, and to return all moving parts to such positions as are necessary to be in readiness for another cycle. This spacing and repositioning is accomplished during the last one-third of the cycle.

A cam 90, see Figures 2 and 16, secured to the main shaft 35 near its forward end, revolving 360 degrees per cycle of the machine, is so shaped as to push a slide bar 91 downwardly at the beginning of the printing operation, i. e., the second third of the cycle, and to release it at the completion of this operation. A lever 92, pivoted to the frame 30 as at 93, see Figure 17, is pivotally connected at one end to the lower end of the slide bar 91 and has its other end bifurcated and in contact with the underside of a flange on a vertically movable rod 94, so shaped as to clamp the printing disc 63 when moved upwardly. A compression spring 95 mounted between the frame 30 and the lower end of the rod 94 urges this rod 94

out of contact with the printing disc 63 and keeps the slide bar 91 in contact with the cam 90. This clamping action on the printing disc 63 obviates any danger of the character being inadvertently moved during the printing operation. A second hump on the cam 90 also causes the disc to be locked during the stop between cycles.

Immediately in front of the disc clamping cam 90 a cam 155 is secured to the shaft 35. The purpose of this is to raise the pawl 57 back to the surface of the blocks 45 at the beginning of the printing third of the cycle of the machine and to disengage it from the selection cog wheel 48 so that it will arrive at the other side of the machine correctly positioned for operation in the next cycle. This is accomplished by means of a slide bar 156 which rides on the surface of the cam 155 and which through an arm 157, a shaft 158, rotatably mounted in the frame 30, and a second arm 159 slides a plunger 160 from a retracted position where it picks up the pawl 57 at the end of the first third of a cycle to the position shown in Figure 7. The cam 155 is so shaped that the plunger 160 is retracted just after the beginning of a cycle when the pawl 57 has moved beyond the surface of this plunger 160, thus remaining in readiness to receive the next used pawl 57 during the selecting or first one-third of the cycle.

The shaft 158 has another lever 162 secured thereto which is connected with the cross bar 391 in such a manner that, when the cam 155 retracts the plunger 160 as described above, the bar 391 is raised so as to hold the boss 39' which has been moved by a depressed key. It is so held until the end of the first one-third of the cycle.

A third 120 degree segment gear 99 is secured to the main shaft 35 which during a variable portion of the final third of the cycle, i. e., the repositioning operation, engages another 120 degree segment gear 100 which is secured on the rearward end of a repositioning shaft 101 rotatably mounted in the frame 30 of the machine. The forward end of the shaft 101 carries a gear 105 which through a pinion 106, see Figure 3, turns the gear 59 which, as previously described, is mounted on the shaft 50 and is in positive connection through bolt 60 and the type disc rotating pinion 61, with both the cog wheel 48 and the character disc 63.

Since the gear 59 is secured to the cog wheel 48 the operation of the segment gear 99 on the segment gear 100 turns the cog wheel 48 in the opposite direction from its previous movement during the character selection operation, which movement was through the angle ϕ . It will be seen that when the cog wheel 48 was first turned through the angle ϕ that the segment gear 100 was at that time turned a proportionate amount from its initial position. The gear ratio is such that during the first one-third of the cycle the segment gear 100 is never turned through a greater angle than the 120 degree segment gear 99 is able to return it during the last one-third of the cycle.

During the printing operation or second one-third of a cycle the segment gear 100 remains stationary as shown in parts "C" of Figures 20 and 21, and the segment gear 99 comes to the position shown in Figure 21 "C." During the repositioning operation or final one-third of a cycle the gear 99 goes from the position shown in Figure 21 "C" to that shown in Figure 19 "C" moving the gear 100 back by the amount it was moved from its initial position, hence moving both the cog

wheel 48 and the type disc 63 back to their starting positions in readiness for the next cycle. The spacing of the copy is accomplished after the printing operation and during the repositioning operation.

In order to vary the spacing of the copy in accordance with the various widths of the characters used on the printing disc 63, a spacing disc 96 is rotatably mounted on a shaft 97 which is longitudinally slidably mounted in the frame 30. The spacing disc 96 has a groove cut in its periphery for each character of one font of type, such as is shown at 98 in Figure 10, the relative positions of the grooves on the spacing disc 96 being the same as that of the characters on the printing disc 63 and their depths being proportional to the widths of the various characters. A chain gear 102 is secured to the repositioning shaft 101 and by means of a chain 103 is connected with a chain gear 104 which is secured to the spacing disc 96.

During the first third of the cycle the chain gear 102 and hence the spacing disc 96 are freely driven by the shaft 101 which is turned by the cog wheel 48 through the gear 59 and the pinion 106. The gear ratio from the type disc 63 to the spacing disc 96 is one-to-one and hence the proper groove 98, having a depth proportional to the width of the character placed in the printing position, is in the same position with respect to the frame 30 of the machine regardless of which of the keys 37 is depressed. At the opening of the groove which is in this position there is a pin 107 the function of which will be apparent from the following description.

A lever 108, pivotally mounted at 109, has one end bearing against a cam 110 which is secured to the shaft 84 and the other end 111 bifurcated and engaging the longitudinally slidable shaft 97. When the lever 108 is moved in opposition to a compression spring 112, the spacing disc 96 is shifted from the position shown by solid lines in Figures 11 and 12 to that shown by broken lines, causing the groove 98 to come into the path of the pin 107.

Immediately following the positioning of the spacing disc 96, a cam 113, mounted beneath the gear 65 on the shaft 66, operates to cause a tooth 114 formed on a spacing release lever 115 to engage a tooth on the periphery of a spacing ratchet wheel 116 thereby locking the ratchet wheel 116 against rotation. A small tension spring 117, connected between the lever 115 and the frame of the machine, keeps a roller 118 on the end of the lever spacing-release 115 in contact with the cam 113. The lever 115 is pivoted, as at 119, to the frame 30 of the machine. When the cam 113 permits the lever 115 to move, as just described, a dog 120 is disengaged from the ratchet wheel 116. The dog 120 is on one arm of a lever 121 the other arm of which carries the pin 107. The lever 121 is pivoted to a lever 122 which is pivotally mounted on the shaft 123 to which the ratchet wheel 116 is secured. A small tension spring 124 connected between the frame 30 of the machine and one arm of the lever 122, causes the levers 122 and 121, upon the release of the dog 120, to move in the direction for the pin 107 to travel into the groove 98. Each groove 98 is so curved that, when the spacing disc is so oriented that the groove being used is in the proper location, the center of its curvature is at the axis 123. When the pin 107 reaches the end of the groove 98 the lever 121 is thereby moved to reengage the dog 120 in

the ratchet wheel 116, the dog 120 having skipped a number of teeth corresponding to the width of the character being printed. At this time the spacing disc 96 is released by the action of the cam 110 on the lever 108 which permits the compression spring 112 to move the spacing disc 96 back to the position shown by solid lines in Figure 12 again out of the plane of the pin 107. The spacing release lever 115 then returns to the position shown in Figure 10, the tooth 114 releasing the ratchet wheel 116 which revolves in a clockwise direction due to tension on a copy carriage 125. This turning of the ratchet wheel 116 is terminated when the lever 122 secured thereto carrying the dog 120 hits a stop 126 on the frame 30. Thus the carriage is permitted to travel a distance corresponding to the width of the character just printed.

Before the completion of the printing third of the cycle the printing head 76 is withdrawn from contact with the back of the copy 89 slightly before the end of the revolution of the cam 67. This is to permit the cam 113 to release the ratchet wheel 116 only after the printing has been completed, but before the gear 65 ceases its operation with the end of the second third of the cycle.

The copy carriage comprises a pair of vertical brackets 125 mounted on a plate 138 which is laterally slidably mounted on rollers held in a way 139 formed in the frame 30. The underside of the plate 138 carries a plurality of racks 140 across its length. For each of the racks 140 there is a pinion 141 rotatably mounted on the ratchet wheel shaft 123, each of the pinions 141 having a keyway 141'. Two pairs of copy holding and indexing rollers 143 are rotatably mounted between the brackets 125, and are so located that the printing heads 76, 77 and 78 will operate between them. Knurled handles 144, mounted on the extremities of two of the indexing roller shafts, provide means for moving the copy paper 89 up or down between the printing heads 76, 77 and 78 and the disc 63. Guides 145 are provided to care for the ends of the copy 89 which protrude from the rollers 143. The plate 138 is connected to the ratchet wheel 116, through the racks 140, the pinions 141, and a key 142 secured on a longitudinally slidable rod 146 which is mounted on the shaft 123.

The keyways 141' in the pinions 141, shown in Figure 22, are so placed that they are in alignment when the copy carriage is at the extreme right position for the beginning of a line of printing. At this position the key 142 may be shifted to engagement with any one of the pinions 141 by means of a lever 147 which is pivoted to the frame 30 and has a bifurcated end which engages a grooved collar 148 which is mounted on the shaft 123 and is secured to the slidable key rod 146. This permits the key 142 to rotate with the shaft 123 and yet be shifted at any point where the keyways 141' are in line. The outer end of the lever 147 is provided with a handle and the frame 30 is notched as at 147' so that the key 142 will engage only one of the pinions 141 at a time.

A slip ratchet 161 of a well-known type is mounted in the shaft 123 so that the copy carriage may be pushed to the right at any time and yet may be driven to the left by the shaft 123 with each cycle of the machine.

A carriage spring of the conventional type used on typewriters which urges the copy carriage to the left and the ratchet wheel 116, as shown

in Figure 10, to rotate clockwise is shown at 149 in Figure 7. Since the motion of the copy carriage per cycle must be dependent upon the size of the font of type in use, for correct spacing, and since the relative motions of the plate 138 and the ratchet wheel 116 must be so proportioned, the gear ratios between the pinions 141 and the racks 140 are such as to accommodate the proportional spacing between the several fonts. The change in this ratio is accomplished by shifting the longitudinal position of a key 142, to cause the proper one of the pinions 141 to drive the ratchet wheel 116 through the common shaft 123.

The type 63' on the face of the printing disc 63 is inked by means of well-known rollers, a large conical roller 150 wiping through an ink trough 151 and contacting two smaller conical rollers 152 so shaped as to roll on the face of the type 64 without slippage as the disc 63 is turned. A thin metal baffle 153, secured to the frame 30, shown in Figures 2 and 24, protects the paper 89 from being soiled by the inked type 64. Apertures 154, cut in the baffle 153 opposite the printing heads 76, 77 and 78, permit the paper 89 to be pressed against the character which is in the printing position.

It is understood that various changes and modifications may be made in the embodiment illustrated and described herein without departing from the scope of the invention as defined by the subjoined claims. It will also be realized that the three phases of the cycle of operation described may each occupy a portion of the total time cycle of operation which is more or less than one-third of such cycle. This may readily be effected by changing the angular extent of the segmental gears 51, 64 and 99 so that they are either more or less than the approximately 120° extent disclosed herein. So, it will be understood that whenever necessary or desirable, the duration of one or more of the phases of the cycle may be increased or diminished with respect to the other phases, provided the selecting phase and the restoring phase do not overlap. Accordingly, within the broader aspects of the invention it is understood that wherever "one-third" of a cycle is mentioned in the present application, it is meant only in a descriptive sense and not in a limiting sense.

Having thus described the invention, what is claimed as new and desired to be secured by Letters Patent is:

1. In a printing machine a fixed member carrying a plurality of slidable blocks which form a substantially smooth surface, keyboard controlled means for moving one of the blocks to leave a space in said surface, a member mounted for movement along a path against said surface, through any space left in said surface by the displacement of a selected one of said blocks, and along a further path of movement thereafter, means for moving said member a predetermined distance along said combined paths, means for biasing said member toward said surface during its movement along said first path, and means controlled by said member during its movement along one of said paths for automatically selecting a character of type and moving the selected character to a predetermined location preparatory to printing, the particular character selected depending upon the relative lengths of the two paths of movement of said member, which is determined by the particular block selected for displacement.

2. In a printing machine a fixed member carrying a plurality of slidable blocks which form a substantially smooth surface, keyboard controlled means for moving one of the blocks to leave a space in said surface, a member mounted for movement along a path against said surface, through any space left in said surface by the displacement of a selected one of said blocks, and along a further path of movement upon the opposite side of said blocks in the same general direction, means for moving said member a predetermined distance along said combined paths, means for biasing said member toward said surface during its movement along said first path, means controlled by said member during its movement along one of said paths for automatically selecting a character of type and moving the selected character to a predetermined location preparatory to printing, the particular character selected depending upon the relative lengths of the two paths of movement of said member, which is determined by the particular block selected for displacement, and means for automatically restoring the member to the original surface of the blocks after it has completed its predetermined total movement over and under all of the blocks.

3. In a printing machine of the class described, adapted to operate in a three-phase cycle upon the depression of a key, to first select and position a type character for impression, next to print the character, and then to restore the machine to its original condition for a subsequent cycle, in combination, a character selecting and positioning mechanism comprising a selecting element, means for moving said element a definite predetermined distance and along a definite path of movement unless diverted, during the first phase of said cycle, keyboard actuated switching means operable to selectively divert said member from said path at any one of a number of points to follow a second path for the remainder of said predetermined distance, means controlled by said element during its movement along one of the paths traversed thereby for automatically selecting a character of type and moving the selected character to a predetermined location preparatory to printing, the particular character selected depending upon the ratios of the lengths of the two respective paths traversed by the selecting element, which is in turn determined by the variable switching means, means for locking the selected type character in said position during the printing phase, and means for restoring said character to its original position during the third phase of the cycle.

4. In a printing machine of the class described, adapted to operate in a three-phase cycle upon the depression of a key, to first select and position a type character for impression, next to print the character, and then to restore the machine to its original condition for a subsequent cycle, in combination, a character selecting and positioning mechanism comprising a rotary member carrying type in a fixed path, a cog-wheel geared to said rotary member to rotate in a constant ratio therewith, an arcuate shield disposed adjacent the periphery of said cog-wheel, an element movable along said shield and about the periphery of said cog-wheel for a definite distance, means for biasing said element toward said shield, keyboard controlled means for providing openings in said shield at selected points, and means for moving said element whereby said element follows said shield for a portion of its movement, moves through the selected opening

into engagement with a tooth of said cog-wheel and continues its movement for the remainder of said distance thus engaged, to rotate the cog-wheel and thus the type carrying member to dispose a selected type in impression position, the particular type so disposed depending on the distance the cog-wheel is moved, which is in turn determined by the point of selective opening of the shield.

5. A movable member carrying type in a fixed path, means for supporting a paper web for movement in a path parallel to a type face, a printing head on the opposite side of the paper path from the type, means for causing the printing head to press paper so supported against the type, a fixed member carrying a plurality of slidable blocks which form a substantially smooth surface, keyboard controlled means for moving one of the blocks to leave a space in said surface, a member mounted for movement over said surface and adapted to move through any space left in said surface and to continue its movement along said blocks on the opposite side of the same, means for moving said member and for biasing it toward said surface, and means comprising a cog wheel, rotatably connected with the type carrying member, so mounted that the member mounted for movement over the surface of the blocks will engage the cog wheel upon having moved through a space in the surface of the blocks, whereby the cog wheel and the type carrying member will each thereby be rotated through predetermined angles.

6. In a printing machine, in combination, a supporting frame, a movable member carrying type in a fixed path, means for supporting a paper web for movement in a path parallel to a type face, a printing device on the opposite side from the type of paper so supported for contacting said paper and moving it against said type, said printing device comprising an element slidably and pivotally mounted on said frame, and a printing head mounted on said element for limited rocking movement, said head having an arcuate paper contacting surface, means for sliding and rocking said element to bring said printing head into contact with said paper and press said surface against the paper with a rolling motion, and spring means urging said head toward one of its limits of movement.

7. In a printing machine, in combination, a supporting frame, a movable member carrying type in a fixed path, means for supporting a paper web for movement in a path parallel to a type face, a printing device on the opposite side from the type of paper so supported for contacting said paper and moving it against said type, said printing device comprising an element slidably and pivotally mounted on said frame, and a printing head mounted on said element for limited rocking movement, said head having an arcuate paper contacting surface, means for sliding and rocking said element to bring said printing head into contact with said paper and press said surface against the paper with a rolling motion, spring means urging said head toward one of its limits of movement, and means for mounting said spring means paracentrically with respect to the rockable mounting of said head, whereby movement of said head beyond dead-center disposes it in an inoperative position.

8. In a printing machine of the character described, a movable member for carrying type in fixed paths, a plurality of type characters carried by said member and arranged in parallel rows,

means for supporting a paper web for movement in a path parallel to the face of the type, a plurality of printing devices on the opposite side from the type of the paper so supported, there being one printing device for each row of type, each of said printing devices including a movable printing element and a printing head mounted on said element for limited rocking movement to contact the paper with a rolling motion, means for moving said printing elements toward the paper and type, spring means urging each of said heads toward one of its limits of movement, and means for mounting said spring means peripherally with respect to the rockable mounting of said head, whereby movement of any of said heads beyond dead-center will dispose them in an inoperative position, all whereby the printing devices opposite the rows of type characters not to be used may be rendered ineffective.

9. In a printing machine, in combination, a supporting frame, a movable member carrying type in a fixed path, means for supporting a paper web for movement in a path parallel to a type face, a printing device on the opposite side from the type of paper so supported for contacting said paper and moving it against said type, said printing device comprising a sleeve pivotally mounted upon said frame, a bar slidably mounted within said sleeve, and a printing head mounted on one end of said bar for limited rocking movement, said head having an arcuate paper contacting surface, spring means urging said head toward one of its limits of movement, spring means urging said sleeve and said bar toward retracted positions, cam means for projecting said bar toward said paper to bring said printing head into contact therewith, and another cam means synchronously connected with said first cam means for rocking said sleeve on its pivot to cause the arcuate paper contacting surface of said printing head to roll over the paper.

10. In a printing machine, in combination, a planar vertically disposed rotary type carrying plate, a plurality of type characters arranged in a circular series of radial rows on said plate, inking means for said type characters comprising a frusto-conical distributing roller adapted to be contacted by said characters during movement of said plate, means for supporting a paper web for movement in a path parallel to the faces of the type characters, an impression member disposed at an impression position on the opposite side of the paper path from the type characters, means for rotating said plate in its own plane with respect to said impression member and so as to position selected type characters in an impression position adjacent said impression member, and a smudge shield intermediate the type path and the paper path and having an aperture therein at least as large as the largest type character carried by said plate, said aperture being located opposite the impression member at said impression position, whereby said paper is pressed through the aperture in the shield and against the selected type character.

11. In a printing machine of the class described, adapted to operate in a three-phase cycle upon the depression of a key, to first select and position a type character for impression, next to print the character, and then to restore the machine to its original condition for a subsequent cycle, in combination, a character selecting and positioning mechanism comprising a rotary member carrying type in a fixed path, key-

board controlled means for selectively rotating said type carrying member through such an angle that a desired type is placed in a predetermined position for printing during said first phase, a locking device for said member, and a single element driven throughout the cycle of operation for actuating said locking device during the entire printing phase, and at a definite point at the end of the cycle between the third phase thereof and the first phase of the next succeeding cycle, and for releasing said locking device during substantially the entire first and third phases.

12. In a printing machine of the class described, a character selection mechanism for moving a type character into printing position, a printing mechanism for obtaining an impression from said type character at said position, a mechanism for restoring the character selection mechanism to initial positions for subsequent operations, and means for actuating said character selection mechanism, said printing mechanism, and said restoring mechanism, comprising, in combination, a shaft, means for driving said shaft through a definite angle of rotation, three segment gears secured to the shaft, means adapted to be engaged by and actuated by one of said segment gears and operatively connected with said character selection mechanism to drive the latter, means adapted to be engaged by and actuated by 30 said second segment gear and operatively connected with said printing mechanism to drive the latter, and means adapted to be engaged by and actuated by 35 said third segment gear and operatively connected with the mechanism for restoring the character selection mechanism for driving said restoring mechanism.

13. In a printing machine of the class described, a character selection mechanism for moving a type character into printing position, a segment gear rotated thereby through an angle dependent upon the character selected, a printing mechanism for obtaining an impression from 40 said type character at said position, a shaft, means for driving said shaft through a definite angle of rotation, three segment gears secured to the shaft, means for operatively connecting one of said three segment gears with said character selection mechanism to drive the latter, means operatively connecting the second of said 45 three segment gears with said printing mechanism to drive the latter, and means including said first named segment gear for operatively connecting the third of said three segment gears with the character selection mechanism for restoring the latter to its initial position.

14. In a printing machine of the class described, in combination, a movable member carrying type in a fixed path, means for supporting a paper web for movement in a path parallel to the type faces, a printing mechanism on the opposite side of the paper path from the type and adapted to press paper so supported against selected ones of said type characters, a character selection mechanism comprising a fixed member carrying a plurality of slidable blocks which form a substantially smooth surface, key-board controlled means for moving one of the blocks to leave a space in said surface, a selector member mounted for movement over said surface and adapted to move through any space left in said surface and to continue its movement along said blocks on the opposite side of the same, means 70 biasing said selector member toward said surface.

face, and means comprising a cog wheel, rotatably connected with the type carrying member and disposed upon the said opposite side of said blocks whereby said member upon passing through a space in the block surface will engage the cog wheel and rotate the latter during its said continued movement, whereby said cog wheel will be rotated through a predetermined angle depending on the character selected and the block displaced, a segment gear operatively engaged with 10 said cog wheel and rotated thereby through an angle dependent upon the character selected, a shaft, means for driving the shaft through a definite angle of rotation, three segment gears secured to the shaft, means for operatively connecting one of said three segment gears with said character selection mechanism for driving the latter, means operatively connecting the second of said three segment gears with said printing mechanism for driving the latter, and means including said first named segment gear for operatively connecting the third of said three segment gears with the character selection mechanism for restoring the latter to its initial position.

15. In a printing machine of the class described, adapted to operate in a three-phase cycle upon the depression of a key, to first select and position a type character for impression, next to

print the character, and then to restore the machine to its original condition for a subsequent cycle, in combination, a character selection mechanism for moving a type character into printing position, a printing mechanism for obtaining an impression from said type character at said position, driving means for said machine adapted to operate it through a single cycle upon depression of a key, and three separate transmission means automatically engageable sequentially by said driving means for respectively operating said selection mechanism, operating said printing mechanism, and restoring said selection mechanism to its initial position for subsequent operations, each of said transmission means being disconnected during the two phases in which its driven mechanism is not operative.

16. A printing machine according to claim 15, in which the third named transmission means includes an element which is moved proportionately to the selecting movement of the type carrying member during the first phase and is readily engaged with the driving means at the beginning of the third phase at whatever position it may have reached during its first movement, and is adapted to be restored only to its initial position by said driving means, whatever the necessary amount of movement to effect this may be.

ROSWELL S. REID.
